(57) **CLAIM**

The ornamental design for a venous access port assembly, as shown and described.

DESCRIPTION

FIG. 1 is an isometric view of a venous access port assembly according to the present invention, taken near the distal end thereof.

FIG. 2 is an isometric view of the venous access port assembly shown in FIG. 1, taken near the proximal end thereof.

FIG. 3 is a distal end view of the venous access port assembly shown in FIG. 1.

FIG. 4 is a proximal end view of the venous access port assembly shown in FIG. 1.

FIG. 5 is a bottom view of the venous access port assembly shown in FIG. 1.

FIG. 6 is a top view of the venous access port assembly shown in FIG. 1.

FIG. 7 is a right side view of the venous access port assembly shown in FIG. 1; and,

FIG. 8 is a left side view of the venous access port assembly shown in FIG. 1.
